WALL MOUNTED LIQUID DISPENSER

Arthur T. Kuehner, Santa Monica, Calif., assignor to Indco Lab. Corporation, a corporation of California

Filed Apr. 4, 1962, Ser. No. 69,574

Term of patent 3½ years

(Cl. D4—3)

FIG. 1.

FIG. 2.

FIG. 3.

FIG. 4.

FIG. 5.

I claim:

The ornamental design for a wall mounted liquid dispenser, substantially as shown.
